UNITED STATES PATENT OFFICE.

DONALD S. BARROWS, OF ROCHESTER, NEW YORK.

FURNACE.

1,416,438.

Specification of Letters Patent. Patented May 16, 1922.

Application filed July 29, 1919. Serial No. 313,986.

To all whom it may concern:

Be it known that I, DONALD S. BARROWS, a citizen of the United States, residing at Rochester, in the county of Monroe and 5 State of New York, have invented certain new and useful Improvements in Furnaces; and I do hereby declare the following to be a full, clear, and exact description of the invention, such as will enable others skilled 10 in the art to which it appertains to make and use the same.

The invention relates to furnaces, and more particularly to improvement in roof members for furnaces used in the re-melting 15 of pig iron with steel, cast iron or malleable iron scrap for the production of grey iron or malleable iron castings.

The principal object of my invention, broadly stated, is to provide metallic 20 movable roof members or bungs as they are commonly called, with means for reinforcing the lower portion thereof, said means also serving to protect the said portions from distortion due to the intense heat within the 25 furnaces and from the destructive action of the furnace gases.

Another object of the invention is to provide a bung with self-adjusting clamping 30 means for holding the roof bricks in assembled position, said clamping means being so arranged as to maintain a substantially uniform pressure over the entire area of the roof bricks or refractory lining of the furnace bung.

35 There are other objects of the invention which will be hereinafter more fully described in connection with the single embodiment of my invention which I have chosen for the purpose of illustration. In 40 the drawings:

Figure 1 is a side elevation of a portion of a furnace bung showing the invention applied thereto,

Figure 2 is a perspective view of one of 45 the detachable lower flange members, and

Figure 3 is a section on line 3—3 of Figure 1, the direction in which the view is taken being indicated by the arrow.

Throughout the specification and drawings like parts are designated by like reference characters.

50 Before describing the invention in detail it might be pointed out that the lining of melting furnaces and such portions of the structural frame work as are subjected to 55 relatively high temperatures are subject to

rapid deterioration in use, and it has been found that the straightening or renewing of the metallic roof members when formed by rolled steel I-beams bent to form an arch is 60 one of the principal items of expense in the maintenance of such furnaces. Each of these I-beam bungs is provided on its lower flange with a lining of refractory material, generally in the form of fire bricks, these 65 in turn forming a section of the furnace roof. These bricks are maintained in place and in contact with the lower flange of the I-beam bung by various mechanical means, the most usual being some form of clamp 70 by which pressure can be exerted upon the series of brick to keep them in close contact with one another and with the bottom flange of the I-beam. When a furnace roof is built up in sections in this manner it is possible 75 to repair breaks in the roof quickly by removing a defective bung and substituting a new bung in place thereof. It should be understood that the bung frames are usually assembled with their refractory linings 80 clamped in position and then placed in position by suitable machinery on the furnace side walls, either separately or in groups of two or more.

This type of furnace bung has the advantage of being lighter than those in which the bung frame is a casting, but it has certain defects among which may be named the following:

(1) Expansion of the lower flange of the 90 I-beam bung frame caused by the extreme heat to which it is subjected, and the small amount of radiating area which said flange presents.

(2) Rapid burning or melting away of 95 portions of this lower flange when through a defect in the refractory lining or otherwise flames from the interior of the furnace play directly upon such flange.

(3) Either of the defects mentioned above 100 create a tendency of the bung frame to straighten out and not retain its original arched form, this tendency also operating to relieve the previously applied clamping pressure on the refractory lining and causing portions of the latter to be released and fall from the bung into the furnace.

(4) Failure of the usual type of clamping means to maintain uniform pressure on the refractory lining, such clamping means 110 usually not providing for the unavoidable variation in total length of the lining when

composed of separate fire brick. If the total length of such lining measured along the length of the bung frame should exceed the length for which the clamping means is designed to operate satisfactorily, the clamping pressure is usually localized on a plane near the top of said lining and this incorrect application of clamping pressure frequently defeats the object for which the clamping means is designed by forcing the lining from contact with the bung frame instead of holding said lining in close contact with the frame.

By my invention the defects described above are eliminated and a furnace bung is provided which is relatively light and easy to handle and comparatively cheap of construction and maintenance.

Referring now to the drawings 1 designates a furnace bung of the usual construction comprising an I-beam having a top flange 2, a web 3 and a lower flange 4. At the center of the upper flange 2 is provided a link or clevis A the object and purpose of which is to provide means connecting the bung to the hoisting apparatus to permit the assembly and removal of the furnace bung from the furnace.

The numeral 5 indicates a plurality of flanged protecting members each of which preferably comprises a web 6 and a flange 7, the latter being provided with an undercut groove 8. The flange and web are preferably connected at a plurality of spaced points by means of the laterally projecting ribs 9. At their ends the flanged member 5 are each preferably provided with perforated flanges 10. The perforations 11 serving, if desired, to receive bolts 12 or other equivalent fastening means for connecting the adjacent ends of the flanged members when in position. The bolts 12 are preferably provided with slots 13 to receive taper keys 14 to maintain the bolts in assembled position. Intermediate some of the ribs 9 the web 6 of the members 5, may be and preferably are provided with bolt receiving openings 15, adapted when the members 5 are assembled on the bung to register with like openings 16 provided in the web 3 of the said bung, the said openings are adapted to receive the fastening bolts 17 which connect the members 5 to the bung 1. The flanged members 5 are adapted to be applied to the opposite sides of the lower portion of the bung in aligned pairs, the grooves 8 in the members 5 being adapted to receive the adjacent portions of the bung flange 4.

It will be readily apparent from the drawings that the members 5 form a housing surrounding the lower flange 4 of the bung and serve to protect the latter from injury. Not only do the flange members give protection to the lower flange of the bung, but in addition they greatly increase the effec-

tive width of the bung flange and hence permit the use of bricks of increased length in connection with each bung. This increase in length of the bricks in a furnace roof decreases the number of bungs required to complete the roof and materially decreases the cost of construction.

To maintain effectively the large size bricks diagrammatically illustrated at 18, in position on the bung I preferably provide each bung with suitable clamping members. For convenience of illustration I have shown but a portion of a bung but it is to be understood that the clamping member illustrated may be duplicated at the opposite end of the bung if desired although it is possible to employ but a single clamping member for each bung.

Adjacent the end of the upper flange 2 of each bung I provide a shoe 19 which may be furnished with a curved or concave face 20. The said shoe is rigidly connected to the said flange in any suitable manner. A lever 21 is provided, the said lever being pivotally connected to a projection 22 extending from the web 3 of the bung, by means of a bolt or pivot pin 23. The said lever is provided adjacent one end with an adjustable set screw 24 the inner end of which is adapted to bear on the curve face of the shoe 19. The opposite end of the lever 20 is provided with a concave face 25 adapted to engage a correspondingly curved faced block 26 which in turn bears against the flat face of one of the lining bricks 18. Owing to the curved faced contact between the lever and the block 26 the line of pressure through the bricks will always be maintained substantially adjacent the center thereof, thus maintaining a constant and even pressure through all of the lining bricks without any distortion or tendency to separate the bricks at either top or bottom.

Having now described my invention in detail, although it is to be understood that the foregoing description is to be taken in the descriptive and not the limiting sense, since what I claim and desire to secure by Letters Patent is:—

1. A furnace bung comprising a metallic member and a lining of refractory material, and means interposed between said lining and the said member for protecting the latter.

2. A furnace bung comprising a flanged member and a lining of refractory material, and means interposed between said lining and the flanged member for protecting the latter.

3. A furnace bung comprising a flanged member and a lining of refractory material and flanged means interposed between the lining and the said member for protecting the latter.

4. A furnace bung comprising a flanged

member and a lining of refractory material and a plurality of flanged members interposed between the lining and the flanged member for protecting the latter.

5. A furnace bung comprising a flanged member and a lining of refractory material and a plurality of members interposed between the flanged member and the lining for protecting the said member and means for 10 connecting the said members to the said flanged member.

6. A furnace bung comprising a flanged member and a lining of refractory material and a plurality of members interposed between the flanged member and lining, said members being adapted to embrace one of the flanges of said flanged member to protect the latter.

7. A furnace bung comprising a flanged member and a lining of refractory material and a plurality of members interposed between the flanged member and lining, said members each being provided with a slot

adapted to receive one of the flanges of the said flanged member, said members serving 25 to protect the flanged member.

8. A furnace bung comprising a member and a lining of refractory material, means for maintaining said lining in position said means comprising a lever provided with a 30 concave face and block interposed between said lever and said lining said block having a convex face adapted to contact the said face on the lever.

9. A furnace bung comprising a metallic member and a lining of refractory material, means for maintaining said lining in position said means comprising a lever pivoted to the said bung, a block interposed between the lining and one end of said lever, said 40 lever and block being provided with symmetrically curved contacting faces and means for applying pressure to the opposite end of the said lever.

In testimony whereof I affix my signature. 45
DONALD S. BARROWS.
